FIG. 6.

INVENTOR.
Michael Tabellione
BY
H. G. Manning
ATTORNEY

This is a continuation-in-part of my application for a patent filed on January 12, 1943, Serial No. 500,384, and for the reasons given in the original application, reference is made to the same for a detailed description of the invention, and the following description is to be construed as an extension of the disclosure of the original application.

UNITED STATES PATENT OFFICE

2,382,831

WRECKING BAR

Michael Tabellione, Meriden, Conn.

Application October 19, 1944, Serial No. 559,384

3 Claims. (Cl. 254—25)

This invention relates to mechanic's tools, and more particularly to a combination tool which may be used as a wrecking bar, nail extractor, shingle remover, etc., and which is especially adapted for use in railroad construction work.

One object of the present invention is to provide a tool of the above nature which will be ideal for pulling heavy spikes or nails without bending the nails, and in which the weight of the tool and the curved base of the tool facilitates the nail-pulling operations.

A further object is to provide a tool of the above nature having an elongated handle section and a substantially semi-circular open bottom frame provided with a flat central section having a nail-embracing aperture.

A further object is to provide a device of the above nature in which said bottom frame has a pair of nail-pulling slots at its upper ends, a single nail pulling slot at its central section, and in which said handle is provided with a claw on the upper end thereof, thus providing five separate points at which nails may be extracted.

A further object is to provide a combination wrecking bar and nail-puller of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 represents a front view of the combination tool in elevation.

Fig. 2 is a side view of the same.

Fig. 3 is a bottom view of the same.

Fig. 4 is a transverse sectional view taken along the line 4—4 of Fig. 1, looking in the direction of the arrows.

Fig. 5 is a longitudinal sectional view taken along the line 5—5 of Fig. 1, looking in the direction of the arrows.

Fig. 6 is a longitudinal sectional view of the lower portion of the bottom frame as it appears when the tool is being used for extracting a nail from a floor.

Referring now to the drawing in which like reference numerals denote corresponding parts throughout the several views, the numeral 10 indicates an elongated tapered handle, preferably rectangular in cross section and converging toward the top. The handle 10 has an inclined

top end 11, which is provided with a pair of sharp teeth 12, 13 forming a top nail-pulling claw.

At the bottom of the handle 10, provision is made of an open substantially semi-circular frame 14 comprising a pair of curved concave side top sections 15, 16 between which is a V-shaped slot 17 which may also be used as a nail-pulling claw, said slot 17 having a beveled circular edge 18.

10 The frame 14 has a pair of upturned points 19, 20 at the extremities of the curved side sections 15, 16 said points terminating in a pair of sharp V-shaped claws 21, 22 as clearly shown in Fig. 4.

At the bottom end of the frame 14, provision is 15 made of a pair of convex lower sections 23, 24, which are connected together by a flat base 25, the junction between said base and said sections 23, 24 having rounded shoulders 26, 27.

At the central portion of the flat base 25, provision is 20 made of a circular nail-embracing aperture 28 having a pair of wedge-shaped V-slots 29, 30 at the sides thereof.

Operation

25 In operation, when it is desired to use the combination tool for extracting nails or spikes, the pulling teeth 12, 13, the V-shaped claw 17, the V-shaped claws 21, 22, or the central aperture 28 may be inserted underneath the nail or spike 30 to be removed, and the tool may then be manipulated with a powerful leverage to remove the nail or spike without bending the latter.

One advantage of the present invention is that the bottom frame 14 may be also used as a hammer to drive a nail into the floor or other article, if so desired.

While there has been disclosed in this specification one form in which the invention may be embodied, it is to be understood that this form is 40 shown for the purpose of illustration only, and that the invention is not to be limited to the specific disclosure, but may be modified and embodied in various other forms without departing from its spirit. In short, the invention includes 45 all the modifications and embodiments coming within the scope of the following claims.

Having thus fully described the invention, what is claimed as new and for which it is desired to secure Letters Patent is:

50 1. In a combined nail-puller and wrecking bar, an elongated handle, a substantially semi-circular open bottom frame connected to the lower end of said handle, said frame having a pair of upturned side nail-pulling claws at the upper end thereof, and a central nail-pulling claw at the

junction of said handle with said frame, said frame also having a flat apertured base including a V-shaped interior nail-pulling claw.

2. In a combined nail-puller and wrecking bar, a handle, an open frame connected to the lower end of said handle, said frame having a central nail-pulling claw at the junction of said handle with said frame, said frame also having a flat apertured base provided with an interior beveled V-shaped side slot forming a nail pulling claw provided with a shoulder at one side thereof to form a fulcrum for said tool when said interior nail-pulling claw is being used.

3. In a combined nail-puller and wrecking bar, a handle, an open frame connected to the lower end of said handle, said frame having a central nail-pulling claw at the junction of said handle with said frame, said frame also having a flat apertured base provided with a pair of opposed interior nail-pulling claws, said base being provided with rounded shoulders at the sides thereof to form fulcrums for said tool when said interior claws are being used for nail-pulling.

10 MICHAEL TABELLIONE.
